PUMP

Alfred B. Sabin, Oakland, Calif.

Application September 2, 1936, Serial No. 99,057

6 Claims. (Cl. 103—248)

This invention relates in general to displacement pumps and in particular to displacement pumps wherein the displacement is effected pneumatically rather than by mechanically moving parts.

In general, the object of the invention is the provision of a displacement pump comprising a pump chamber having inlet and outlet check valves at its lower end and provided with means whereby a differential pressure may be alternately created between the inlet check valve and the pump chamber in the direction of the pump chamber and between the pump chamber and the outlet check valve in the direction of the outlet check valve, to alternately fill the pump chamber with slurry and empty it.

Another object of the invention is the provision of an improved check valve.

Still a further object of the invention is the provision of a float operated valve mechanism for controlling the air pressure within the pump chamber in relation to the level of the slurry within the chamber.

The invention possesses other advantageous features, some of which with the foregoing will be set forth at length in the following description where that form of the invention which has been selected for illustration in the drawings accompanying and forming a part of the present specification is outlined in full. In said drawings, one form of the invention is shown, but it is to be understood that it is not limited to such form, since the invention as set forth in the claims may be embodied in a plurality of forms.

Referring to the drawings:

Figure 1 is a transverse vertical section of a displacement pump embodying the objects of my invention.

Figure 2 is a plan view of the displacement pump shown in Figure 1 with the cover of the valve head removed.

Figure 3 is a vertical section taken on the line 3—3 of Figure 1.

Figure 4 is a plan view of the core of one of the slurry check valves.

Figure 5 is an end view of the core shown in Figure 4.

Figure 6 is a vertical section of one of the air valves taken on the line 6—6 of Figure 2 with one of the air valves shown in its open position.

Figure 7 is a vertical section of one of the air valves taken on the line 7—7 of Figure 2 with one of the air valves shown in its closed position.

Figure 8 is a section similar to that shown in

Figure 7 but with the air valve shown in its open position.

Figure 9 is a section taken on the line 9—9 of Figure 8.

Figure 10 is a vertical section taken through a modified displacement valve wherein a rubber diaphragm has been utilized in place of a float.

As best shown in Figure 1, my displacement pump comprises a pump chamber 1 having a general conical body member 2 and terminating at its upper end in a cylindrical portion 3 provided with a flange 4, and at its lower end in a cylindrical member 5 provided with a flange 6. Formed within the pump chamber 1 is a float chamber or cage 7 having vertically extending slots 8 and apertures 9 for establishing communication between the float and pump chambers. Extending laterally of the cylindrical portion 5 is a pair of diametrically opposed cylindrical portions 11 and 12 terminating respectively in flanges 13 and 14. The cylindrical portion 11 is provided with a boss 15 through which is threaded a set screw 16 adapted to be locked in any predetermined position by a lock nut 17. The outer end of the cylindrical portion 11 is provided with inwardly extending beveled lips 18, located opposite to the inner end of the set screw 16. The lower end of the cylindrical member 5 serves as an inspection port and is normally closed by means of a cover plate 10 bolted to the flange 6. An inspection port 20 may also be provided on the rear side of the pump as indicated in Figure 1. The cylindrical portions 11 and 12 serve respectively as a slurry inlet and outlet.

Secured to the flange 13 by any suitable means such as bolts is a slurry intake fitting 19 and secured to the diametrically opposed flange 14 in the same manner is a slurry outlet fitting 21. The fitting 21 is provided with a boss 22 in which is threaded a set screw 23 adapted to be locked in any desired position by lock nut 24.

Disposed within the fitting 21 diametrically opposite the lower end of the set screw 23 are beveled ledges 25. The outer face of the slurry intake fitting 19 is provided with a threaded sleeve 26 and threaded in the sleeve 26 is an elbow 27 which in turn is connected with a conduit 28 communicating with a source of pulp or slurry. Formed on the inner face of the fitting 21 is a threaded sleeve 29 and threaded in the sleeve 29 is a nipple 31. The free end of the nipple 31 extends downwardly towards the lower portion of the pump chamber so that all slurry delivered from the pump is taken from its lowermost portion.

Secured against the inner face of the intake fitting 19 by means of the beveled lips 18 and the set screw 16 is a valve core 32 (see Figures 4 and 5). A similar valve core 33 is secured against the outer face of the outlet fitting 21 by means of the set screw 23 and the beveled ledges 25. If desired, a gasket may be interposed between the valve cores and the faces against which they seat, in order to make a liquid-tight joint. The valve cores 32 and 33 are identical and as shown in Figures 4 and 5 comprise a cylindrical body portion 34 having an annular groove 35. One end of the body portion is provided with beveled lugs 36, while the other end is flattened or pinched and provided with spaced grids 37. Secured over the flattened end of the core by means of a wire band 38 is a short length of flexible hose 39 (see Figure 1). From an inspection of Figure 5, it will be seen that the grid 37 may be considered as defining a long slot passing through the axis of the core and a plurality of transverse slots. These slots permit the egress of slurry from the core while the grids prevent the collapse of the hose into the core when the valve is in its closed position as shown in connection with the core 32 shown in Figure 1. It is contemplated that instead of resorting to a core provided with grids for preventing the collapse of the hose into the core, longitudinally extending wire reinforcements may be molded in the hose.

To the flange 4 of the cylindrical portion 3 forming the upper end of the pump chamber 1 is bolted a flanged valve head 41. Extending upwardly along the axis of the valve head 41 is a rectangular support or post 42 terminating at its upper end in a threaded stud 43 and disposed over the valve head 41 is a cap 44 adapted to seat in a peripheral groove 45 formed in the upper end of the valve head. A gasket 46 may be interposed between the engaging surfaces of the cap 44 and the valve head 41, and a gasket 47 interposed between the engaging surfaces of the cap 44 and the post 42 so that the compartment or air chamber formed by the cap 44 and the valve head 41 may be air tight. A wing nut 48 threaded on the stud 43 serves to lock the cap 44 in a sealed relation to the valve head 41. The lower face of the valve head 41 is provided with a recess 49 and extending upwardly from the recess 49 is a vertical bore 51. Formed on the left hand side of the valve head 41 is a pair of vertical bores 52 and 53 symmetrically spaced with respect to a plane passing through the axis of the bore 51 and the axis of the valve head. The bores 51, 52, and 53 are intersected by a horizontal bore 54. The bores 52 and 53 are also intersected respectively by bores 55 and 56. The right hand end of the bore 54 is threaded to accommodate either a plug or a pipe fitting and the lower ends of the bores 52 and 53 are threaded in order to accommodate plugs 57 and 58. The outer ends of the bores 55 and 56 are threaded in order to receive respectively a low pressure air line connection and a high pressure air line connection or atmospheric connection. Depending from the lower face of the valve head 41 is a bracket 59, to which is pivoted a pair of parallel links 61 and 62, which in turn are pivoted to a link 63. The bracket 59 and links 61, 62, and 63 form a parallelogram by which the link 63 may be made to move only parallel to itself. The link 63 carries a hood 64 and terminates in an eye 65 to which is secured a chain 66. Secured to the lower end of the chain 66 is a float 67. A vent 60 is provided in the hood 64 and also a

number of spaced bosses 68 for the purpose of holding the float 67 slightly spaced from the hood 64, thereby preventing the formation of a vacuum within the hood when the float is in its uppermost position and preventing the float from sticking to the hood. Since the hood 64 is secured to the link 63 and since the link 63 is permitted to move only parallel to itself, the rim of the hood will always maintain a horizontal position, thus insuring the proper seating of the ball 67. Pivoted intermediate the ends of the link 61 is a push rod 69 arranged to operate through the bore 51 and carrying at its lower end a ball valve 71. The primary purpose of the ball valve 71 is to prevent the entrance of slurry into the valve head. To the upper end of the push rod 69 is secured a forked link 72, the free ends of which are provided with vertically extending slots 73. Pivoted to the post 42 is a pair of U-shaped links 74 and 75. A lost motion connection is made between the link 74 and the forked link 72 by means of a pin 76 secured to the link 74 and passing through the slots 73 formed in the link 72. This lost motion connection permits the link 74 to snap unhampered by the inertia of the push rod assembly and hood and permits the ball valve to seat if for any reason there is an abnormal rise of the slurry within the pump chamber. The link 75 carries a pin 77 to which are pivoted valve stems 78 and 79 (see Figure 6 for valve stem 79). Disposed within the upper ends of the bores 52 and 53 are cages 80 and 81 respectively. The cage 80 is provided with downwardly facing valve seats 82 and 83 adapted to receive ball valves 84 and 85 carried by the valve stem 78. The cage 81 is provided with upwardly extending valve seats 86 and 87 adapted to respectively receive ball valves 88 and 89 carried by the valve stem 79. Secured to either end of the pins 76 and 77 are a pair of coil springs 91 and 92. When the pump is being used for pumping relatively dense slurries it is advisable to maintain the slurry within the lower part of the pump chamber in a state of agitation. This may be done by passing a nipple 93 through the cylindrical member 5 and attaching thereto a check valve 94 of the same type as used in connection with the slurry inlet and outlet of the pump. The end of this valve should be located immediately beneath the intake of the nipple 31. The nipple 93 may be connected with any suitable source of fluid under sufficient pressure to produce a jet from the mouth of the check valve 94.

The operation of the displacement pump above described is as follows:

When the pump chamber 1 is empty, the float 67 will be in its lowermost position and therefore the push rod 69 will also be in its lowermost position as shown in Figure 8. With the push rod 69 in this position, the links 74 and 75 will be held in their downwardly extending position by the action of the coil springs 91 and 92. The ball valves 84 and 85 will be in their fully open position while the ball valves 88 and 89 will be in their closed position. The pump chamber 1 may therefore be placed under sub-atmospheric pressure by merely connecting the bore 55 to a suitable source of vacuum. Assuming that the source of pulp or slurry to which the conduit 28 is connected is under atmospheric pressure and is substantially at the level of the slurry intake valve, it will be seen that the pressure differential between the exterior and interior of the pump will cause slurry to enter the pump chamber 1

through the slurry intake valve. Due to this same pressure differential the outlet slurry valve will be maintained in its pinched or closed position. As the float 67 rises within the cage 7, it will engage the hood 64, thereby lifting the push rod 68, and if the float continues to rise, it will cause the ball valve 71 to close the bore 51. When the lower end of the slots 73 formed in the link 72 engage the pin 76, the link 74 will be made to rotate in a counter-clockwise direction about its pivotal point. As the link 74 moves in a counter-clockwise direction, the springs 91 and 92 will pass their dead center position and at this instant the link 74 will snap upwardly in a clockwise direction, thereby seating the ball valves 84 and 85 and unseating the ball valves 88 and 89. Communication between the bore 55 and the source of vacuum to which it is connected will therefore be cut off. If therefore the bore 56 is connected with a source of atmospheric or super-atmospheric pressure, the pump chamber 1 will be emptied by forcing its contents through the outlet slurry valve. During the time that the pump chamber is being discharged, the intake slurry valve will be held in its closed position as shown in Figure 1 by the outwardly directed differential pressure, and due to the same force, the outlet slurry valve is held in its open position.

The pump chamber is preferably made conical in shape so that if it is being discharged by gravity under atmospheric or super-atmospheric pressure the greatest volume of slurry within the pump chamber will have a maximum static head acting on it.

To fill the pump chamber 1 with slurry, all that is required is an inwardly directed differential pressure, and to empty the pump chamber all that is required is an outwardly directed differential pressure. Obviously these differential pressures may be obtained by using atmospheric pressure in combination with sub-atmospheric pressure, atmospheric pressure in combination with super-atmospheric pressure, or sub-atmospheric pressure in combination with super-atmospheric pressure. When the operating differential pressure is obtained by the use of a combination of sub-atmospheric and super-atmospheric pressures it is desirable to vent the pump chamber to atmosphere at the end of each working stroke in order to decrease the load on the vacuum pump. This may be done by the arrangement schematically shown in connection with Figure 1. Inserted in the conduit 111 connecting the vacuum port 55 with a source of vacuum is a check valve 112 and a diaphragm valve 113. The port 54 which as above described is in direct communication with the pump chamber 1, is connected with the diaphragm valve 113 by the conduit 114. The valves 112 and 113 are so constructed and adjusted that when the pressure within the pump chamber 1 is greater than atmospheric, the check valve 112 will remain open, thereby establishing communication between the pump chamber and the atmosphere, and the valve 113 will remain closed, thereby cutting off the source of vacuum. When the pressure within the pump chamber has dropped to atmospheric the diaphragm valve 113 will open and the check valve will assume its closed position due to the action of the vacuum in the conduit 111. It is felt that for one skilled in the art a further explanation of the manner in which a differential pressure may be obtained is unnec-

essary and that the operation of my device will be fully appreciated from the above description.

One of the outstanding uses of a displacement pump of this character is for the purpose of maintaining a constant liquid level in a tank 5 such as for example the pulp tank of a continuous rotary filter. My pump may be used for this purpose by so locating the level of the pump with respect to the desired constant level in the tank 98 (see Figure 1) that the float in its 10 lowermost position is substantially at the desired constant level in the tank. When the tank 98 is open to atmosphere the differential pressure for operating the displacement pump should be obtained by the use of atmospheric and sub-atmospheric pressure, that is, the port 55 should be connected to a source of vacuum and the port 56 to atmospheric pressure. In operations of this kind, although the capacity of the tank 98 is of course many times greater than the displacement of the pump, the capacity of the pump must exceed the outflow from the tank.

In Figure 10 a modified form of the displacement pump has been shown in which the pump chamber 101 is formed by two oppositely disposed dish-shaped members 102 and 103 bolted together through flanges 104 and 105. Secured between the flanges 104 and 105 is a rubber diaphragm 106, the central portion of which is connected to the link 163 by means of the chain 166. 30 Pivoted to the link 163 is a yoke 107 adapted to engage the central portion of the diaphragm 106. The construction of this modification is otherwise identical with that of the pump shown in Figures 1 through 9. It will therefore be seen that the upward movement of the diaphragm 106 against the yoke 107 will cause the valves within the valve head 141 to operate in the same manner as above described.

The term "slurry" as herein used designates 40 any liquid or mixture of liquids and solids capable of being handled by the pump as above described.

I claim:

1. A displacement pump comprising: a pump 45 chamber provided at its lower end with a slurry inlet and with a slurry outlet; a float disposed within said pump chamber; check valves associated with said inlet and outlet; a pair of air valves associated with the upper end of said 50 pump chamber; means associated with said air valves and said float for closing one of said air valves and opening the other when the float assumes its upper position and for reversing the relative positions of these valves when the float assumes its lower position; and means associated with the lower part of said pump chamber for maintaining the slurry content therein in a state 55 of agitation.

2. A displacement pump comprising: a pump 60 chamber provided at its lower end with a slurry inlet and with a slurry outlet; a float disposed within said pump chamber; check valves associated with said inlet and outlet; a pair of air valves associated with the upper end of said pump 65 chamber; means associated with said air valves and said float for closing one of said air valves and opening the other when the float assumes its upper position and for reversing the relative positions of these valves when the float assumes its lower position; and a fluid jet associated with the lower part of said pump chamber for maintaining the slurry contained therein in a state of 70 agitation.

3. A displacement pump comprising: a pump 75

chamber; slurry inlet and outlet check valves associated with the lower end of said pump chamber, said valves being arranged to operate on the application of a differential fluid pressure between the interior and exterior of said pump chamber; a valve head secured to the upper end of said pump chamber; a central support extending upwardly from said valve head; an air chamber formed above said valve head and surrounding said support; a vertical passageway at one side of said support for establishing communication between said air and pump chambers; a pair of air passageways on the other side of said support establishing communication between the interior and exterior of said air chamber; a pair of levers pivoted to said support; a spring secured to the outer ends of said levers for urging the free ends of said levers together; valve seats associated with said three passageways; valves adapted to seat in said seats; valve stems secured at one end to said valves and at the other to said levers; and a float disposed in said pump chamber and connected with a valve associated with said vertical passageway by means of a lost motion connection.

4. A displacement pump comprising: a pump chamber; slurry inlet and outlet check valves associated with the lower end of said pump chamber, said valves being arranged to operate on the application of a differential fluid pressure between the interior and exterior of said chamber; a valve head associated with the upper end of said pump chamber; an air chamber formed in said valve head; a passageway in said valve head communicating with a conduit which in turn communicates with a source of subatmospheric pressure, a second passageway in said valve head adapted to be placed in communication with a source of superatmospheric pressure; valves associated with each of said passageways; means associated with each of said valves for alternately opening and closing one of said passageways and closing and opening the other of said passageways in correlation with the slurry level in said pump chamber; a valve in said conduit responsive to the pressure within said air chamber; and a check valve in said conduit located between the valve and said air chamber and permitting the

escape of air from said air chamber when said air chamber is under super-atmospheric pressure.

5. A displacement pump comprising: a pump chamber; slurry inlet and outlet check valves associated with the lower end of said pump chamber, said valves being arranged to operate on the application of a differential fluid pressure between the interior and exterior of said pump chamber; a valve head associated with the upper end of said pump chamber; an air chamber formed in said valve head; a pair of air passageways in said valve head establishing communication between the exterior of said valve head and said air chamber; valves associated with each of said passageways; snap action means disposed in said air chamber for opening and closing said last mentioned valves; a float disposed in said pump chamber; a passageway establishing communication between said pump and air chambers; means operable by said float and through said last mentioned passageway for actuating said snap action means; and a valve for closing said last mentioned passageway when said float is in its uppermost position.

6. A displacement pump comprising: a pump chamber slurry inlet and outlet check valves associated with the lower end of said pump chamber, said valves being arranged to operate on the application of a differential fluid pressure between the interior and exterior of said pump chamber; a valve head associated with the upper end of said pump chamber; an air chamber formed in said valve head; a pair of air passageways in said valve head establishing communication between the exterior of said valve head and said air chamber; valves associated with each of said passageways; snap action means disposed in said air chamber for opening and closing said last mentioned valves; a float disposed in said pump chamber; a passageway establishing communication between said pump and air chambers; lost motion means operable by said float and through said last mentioned passageway for actuating said snap action means; and a valve for closing said last mentioned passageway when said float is in its uppermost position.

ALFRED B. SABIN.
